ATTORNEY

UNITED STATES PATENT OFFICE.

HUGH McCONNELL, OF CLEVELAND, OHIO.

SAD-IRON HEATER.

SPECIFICATION forming part of Letters Patent No. 243,985, dated July 5, 1881.

Application filed January 7, 1881. (No model.)

To all whom it may concern:

Be it known that I, HUGH McCONNELL, of Cleveland, in the county of Cuyahoga and State of Ohio, have invented certain new and useful 5 Improvements in Sad-Iron Heaters; and I do hereby declare the following to be a full, clear, and exact description of the invention, such as will enable others skilled in the art to which it pertains to make and use it, reference being 10 had to the accompanying drawings, which form part of this specification.

My invention relates to sad-iron holders, and particularly to that class of holders adapted for use in connection with vapor, oil, or gas stoves; 15 and it consists in an inclosed case provided with a handle, said handle so constructed and adapted, in connection with the top, that it can be moved down out of the way when packed and held in that position until released, when it will 20 assume a more upright position, and one in which it can be readily grasped; also, in an improved arrangement by means of which the irons are taken from the holder from the same side; also, in a sad-iron holder adapted to hold 25 and sustain three sad-irons; also, in combination with the doors which close the openings through which the sad-irons pass to the holder, of ribs permanently attached to or made a part 30 of the bottom, said ribs, in conjunction with the side, forming bearings for holding the pivots or journals upon which the doors move, and in parts and combinations of parts, as will more fully hereinafter appear.

In the drawings, Figure 1 is an isometric 35 view of a sad-iron holder constructed according to my invention, showing the relative position of the three irons when the same is in use. The construction shown is adapted to rest upon the drum of an ordinary oil-stove. Fig. 2 is a 40 detached vertical sectional view of the bottom side and top of a sad-iron holder constructed according to my invention, that shows the rib attached to the bottom and the pivot or journal of a door, illustrating the manner in which 45 said pivot or journal is held in place. Fig. 3 is a detached view of a portion of the holder, together with one end of the handle, showing the connection of the handle with the holder, and also the shoulder which prevents the han- 50 dle from moving farther than an upright position in one direction, and also showing the circular face of the holder, which is adapted to

spread the handle when it is closed down about the holder, and when the handle is released to cause it to assume an upright, or substantially 55 upright, position. Fig. 4 is a plan view of the device.

In the said drawings, A represents the bottom of the sad-iron holder, which preferably 60 consists of a solid plate.

Heretofore sad-iron holders adapted for use in oil, gas, or vapor stoves have been more or less open in the bottom. This is objectionable on account of the irons being liable to become smoked or blackened from direct contact 65 with the flame. To obviate this, that portion of the holder immediately beneath the sad-iron is made preferably solid. The bottom A is provided with suitable projections, a, corresponding to similar projections, c, upon the side of 70 the holder, said projections adapted to be riveted or bolted together. The bottom is also provided with a rib, a², which acts as a wall or a portion of the bearing, in which the pivot or journal of the doors turn.

B represents the top of the sad-iron holder, which, together with the side C, is cast in a single piece, said side being provided with projections c, of a shape to conform to the projections a of the bottom.

D represents doors, provided with pivots or journals b, adapted to turn in openings prepared in the sides, as shown at c', and at the other end adapted to turn between the upright C' and the rib a² of the bottom.

B' is a central plate portion of the top, situated between the openings adapted to receive the handles of the two sad-irons at rest within the holder. This plate is adapted to receive and hold the third iron.

E represents a handle, by means of which the holder may be taken from the stove or moved from place to place. This handle is made to conform in its shape to the front circular portion of the holder, and of a size a little, larger than the holder, so that it can be crowded down upon the outer face when packed, and thus permit the holders to be placed closely together. This handle is provided upon either end with hooks adapted to enter recesses in the sides of the holder immediately below the top, as shown in Fig. 1. These recesses or holes for the reception of the handle are provided upon one face with a square shoulder, whereby

the handle can only be moved in that direction to an upright position, while upon the other face it is of circular shape, and adapted to spread the handle or bail as it is borne down upon and give the bail an upward throw when pressure is removed from it.

The operation of my device is as follows: When the sad-iron holder is unpacked and the handle E released it will assume the position 10 shown in Fig. 1, and may be placed upon the stove and the sad-irons placed in openings prepared for them, as shown in the said figure. The third iron is placed upon the plate B', where it will receive a certain amount of heat, 15 which otherwise would be wasted. As soon as one of the irons becomes sufficiently heated it may be taken from the holder for use, while the one resting upon the plate B' may be placed in its stead, so that three irons may be kept 20 constantly in use, two being at all times within the holder.

Heretofore in all sad-iron holders with which I am acquainted, adapted for use with gas, vapor, or oil stoves, it has been necessary to 25 place the irons within the holder from opposite directions, which is found to be exceedingly inconvenient to the person using them. In this holder I have so economized space that

the same result is reached in a much more convenient form.

30

What I claim is—

1. In a sad-iron holder, the combination, with the pintles or journals d of the hinged doors D, of the sides C, and central portion, C', provided with openings for the admission 35 of said pintles, and the bottom A, provided with ribs a², for retaining the pintles in place, substantially as set forth.

2. In a sad-iron holder, the combination of a bail or handle and a solid top provided with 40 a recess for the reception of the ends of the bail, said recess having upon one face a square shoulder, whereby the handle can only be moved in that direction to an upright position, and upon the other face a circular-shaped bearing, adapted to spread the handle as it is borne down upon, and give the bail an upward throw when pressure is removed from it, substantially 45 as set forth.

In testimony whereof I have signed my name 50 to this specification in the presence of two subscribing witnesses.

HUGH McCONNELL.
